UNITED STATES PATENT OFFICE.

HARRY SCHACK, OF NEW YORK, N. Y.

DISPLAY-FORM.

1,163,110.

Specification of Letters Patent.

Patented Dec. 7, 1915.

Application filed May 7, 1915. Serial No. 26,462.

To all whom it may concern:

Be it known that I, HARRY SCHACK, a citizen of the United States, residing at New York city, borough of Manhattan, county 5 and State of New York, have invented certain new and useful Improvements in Display-Forms, of which the following is a clear, full, and exact description.

This invention relates to display forms 10 more particularly for ladies wearing apparel such as neckwear and the like, or anything to be worn about the neck such as chains, etc.

One of the objects of the invention is to 15 provide an economical and cheap device for the purpose named.

Other objects are to provide a practical and efficient display form for such purposes as named, or similar purposes.

20 These being among the objects of the present invention, the same consists of certain features of construction and combinations of parts to be hereinafter described and then claimed with reference to the accompanying 25 drawing illustrating a suitable embodiment of the invention, and in which—

Figure 1 is a perspective view thereof showing a chain and ornament displayed thereon; Fig. 2 is a cross-section thereof on 30 the line 2—2 Fig. 1; Fig. 3 is a plan of the base member showing the connecting portions which are cut thereinto before said base member is formed into proper shape; Fig. 4 is a plan of the blank for the collar 35 or tubular member; and Fig. 5 is a perspective view of the tubular member itself.

Referring to Fig. 3, the base member or breast and shoulder form 10 is of elongated shape so as to provide a forwardly extending apron 11. Preferably the said parts are 40 composed of sheet material such as press-board so that said parts are comparatively stiff, and the sides taper gradually toward the end of the apron. In substantial alignment with the longitudinal central axis of the parts 10, 11, there is cut into the said board a slit 12 which extends through the edge, while at one side of said slit there is 45 cut into the base member 10 a comparatively long slit 13 which is inclined relatively to the slit 12, and at the opposite side of the slit 12 there is located a comparatively wide tongue 14. This tongue is preferably 50 formed by slitting the base member substantially as shown. Located at opposite

sides of the inner end of the slit 12 is a pair of slits 15, 16, which extend in the general direction of the length of the parts 10, 11, while at a point in line with said slit 12 and between the slits 15, 16, there is formed a 60 transverse slit 17. The slits 15, 16 and 17 are formed in a substantial semi-circle concentric with a point adjacent the inner end of slit 12. The tongue 14 and the slit 13 constitute interlocking elements, and it will 65 be seen that by reason of the flexible character of the material the edges of the slit 12 may be moved past each other and the parts overlapped so that the tongue 14 may be engaged in the slit 13. This manipulation 70 connects the overlapped portions by a single joint at the rear and humps up or deforms the base member or breast and shoulder form so as to produce a flattened conical portion 18 shown in Figs. 1 and 2, the apex 75 19 of which is located adjacent the inner end of the slit 12.

In Fig. 4 there is shown a flexible strip 20 preferably of press-board and this is formed at the opposite ends with a transverse slit 21 and a tongue 22 respectively. At one edge of said strip there is provided a series of tongues 23, 24, 25. The said flexible strip 20 is now rolled or bent into tubular shape, in which shape it is retained by the engagement of the tongue 22 with the slit 21, as shown in Fig. 5. Thus a collar or tubular member 26 is provided having tongues 23, 24, 25, at its lower edge. Said tubular member which now constitutes a neck form 80 is now applied to the base member or breast and shoulder form 10 by engaging the tongues 23, 24, 25, in the slits 15, 17, 16, thereby producing the complete device 85 shown in Figs. 1 and 2. When the parts are 90 united, the apical portion of the base member will set into the tubular member. 95

As will be noticed, the exposed front surfaces of the breast and neck forms are preferably free from joints and continuously smooth and unbroken, due to the location of the joints of said forms at the back of the device. It will also be observed that the front portion or apron of the breast and shoulder form is prolonged considerably 100 forward relatively to the remainder of said form, and that when the two described members of the display form are properly connected the said front portion or apron is 105 inclined at a substantial angle away from 110 115 120

the axis of the neck form. The described display form thus comprises a neck form and a breast form which is provided with proper background surfaces for the display 5 of neck-worn articles.

It is obvious that the described display form is composed of the fewest possible parts, namely two, and that it is a very simple matter to construct the display form by 10 making use of the appropriate interlocking elements such as described. The parts described can also be packed and shipped flat and connected up afterward, and the described device may be taken apart so that 15 the parts will resume their original flat condition.

In the illustrated form of the invention the breast portion of the breast and shoulder form has a symmetrically curved peripheral 20 edge and is of relatively great extent as compared with the shoulder portions of said form.

It is obvious that the invention is susceptible of modification, as parts may be omitted, parts added, and parts substituted without departing from the spirit and scope of the invention as expressed in the claims.

What I claim as new is:—

1. A display form for neck-worn articles, 30 comprising two connected formed members, namely, a tubular neck form rolled up from a piece of sheet material, and a breast form bent up from a separate piece of sheet material into a flattened conical shape, said 35 forms having rear separable connecting parts by which they are held in shaped condition, each form being free from any exposed joint in its visible front portion and each of said front portions having an unbroken continuously smooth background- 40 surface, the said front portion of said breast form being inclined at a substantial angle away from the axis of said neck form.

2. A display form for neck-worn articles, 45 comprising two connected formed members, namely a tubular neck form rolled up from a piece of sheet material, and a breast and shoulder form comprising a piece of sheet

material which is elongated relatively to the shoulder portions thereof forwardly beyond 50 said neck form to provide a forwardly extending apron, and which is cut in from its rear edge forwardly toward the axis of said neck form to provide two overlap parts, one of the latter having a single, relatively 55 long, slot, and the other of said parts a single, relatively wide, tongue, said overlap parts being overlapped behind said neck form and the said tongue engaged with said slot, whereby a breast and shoulder form of 60 flattened conical shape is provided, and said apron being inclined at a substantial angle away from the axis of said neck form, each of said forms being free from any exposed joint in its visible front portion and each of 65 said front portions having a smooth background surface.

3. A display form for neck-worn articles, comprising a flexible base member which is slotted laterally through the rear edge and is 70 provided with interlocking elements at both sides of the slit, whereby said member is deformable to provide a flattened conical portion and an apron extending laterally from said conical portion, said parts constituting a breast and shoulder form, and a 75 tubular member consisting of a flexible strip provided with interlocking elements at its ends, said tubular member constituting a neck form having downwardly extending 80 tongues, and the said conical portion of said base member having a series of slits located around its apex and into which latter slits said tongues are interlocked but with the interlocked ends of said strip located at the 85 rear, said apex extending up into said tubular member, and the exposed front surfaces of said display form being continuously smooth and unbroken so as to constitute a 90 display-background.

Signed at New York, N. Y. this 1st day of May, 1915.

HARRY SCHACK.
